HOUSING FOR EXTERIOR ELECTRICAL RECEPTACLES

Robert A. Bozich, Eveleth, Minn., assignor to Malton
Electric Company, Virginia, Minn.

Filed Dec. 9, 1974, Ser. No. 530,692

Term of patent 14 years

Int. Cl. D13—03

U.S. Cl. D26—12

FIG. 1

FIG. 3

FIG. 4

FIG. 2

FIG. 5

FIG. 8

FIG. 6

FIG. 9

FIG. 7

FIG. 1 is a perspective view taken from the front, top and left side of a housing for exterior electrical receptacles illustrating my new design;

FIG. 2 is an enlarged top plan view thereof;

FIG. 3 is an elevational view taken from the side opposite that shown in FIG. 1;

FIG. 4 is a rear elevational view thereof;

FIG. 5 is a perspective view taken from the front, top and left side of a modified form of the housing for exterior electrical receptacles shown in FIG. 1;

FIG. 6 is enlarged top plan view of FIG. 5;

FIG. 7 is an enlarged bottom plan view of FIG. 5;

FIG. 8 is an elevational view taken from the side opposite that shown in FIG. 5; and

FIG. 9 is a rear elevational view of FIG. 5.

I claim:

The ornamental design for a housing for exterior electrical receptacles, substantially as shown and described.
